SHOE STITCHER STRUCTURE

Eugene G. Wolf, St. Louis, Mo., assignor to
 Landis Machine Company, St. Louis, Mo., a
 corporation of Missouri

Application July 17, 1939, Serial No. 284,819

10 Claims. (Cl. 112—57)

The invention relates to sewing machines and particularly the type of leather stitchers used in sewing shoe soles and uppers together, and the invention consists in structure for effecting and releasing thread and presser foot locks.

In most machines of this type it is customary to lock the thread against being pulled from the spool during a substantial portion of the cycle of operations of the machine and more specifically during the "take up" operation in which the surplus thread, fed to the work and drawn through the same by the needle, is pulled back to tighten the stitch.

Also on such machines the presser foot is thrust against the work to hold the work against movement through the machine during the greater part of the machine cycle but this thrust is released for a short period during each cycle to permit the work to be fed the length of the stitch for the succeeding operation.

Previously it has been customary to effect the thread lock by spring pressure and the spring would vary in its thrust, due to temperature conditions and other factors. The cramped space available for the spring makes it difficult or impossible to use a spring as long and as large as is desirable for satisfactory and permanent results.

Usually the presser foot is held in locked position by a ratchet and pawl device, the ratchet teeth being intended to accommodate every variation in the thickness of the work. Obviously, the work may be of a thickness intermediate successive ratchet teeth and obviously wear on the ratchet teeth and the point of the ratchet pawl tend to make the secure locking of the work by the presser foot impermanent even though the ratchet and pawl device were effective initially for a given setting.

The objects of the present invention are to overcome the above difficulties by providing a thread lock and a presser foot lock which will be secure irrespective of the thickness of the thread or the thickness of the work, and which will remain secure irrespective of wear in the parts. It is further desired to construct the lock parts so they will require little space thereby facilitating assembly and replacement and also increasing the accessibility of adjacent mechanisms.

It is a further object of the invention to provide a manual release for the new locking structure whereby both locks may be released simultaneously at any time in the cycle of operations of the machine irrespective of the position of

the machine cams which normally set and release the locks at stated periods in the cycle of operations.

These and other detailed objects of the invention as will appear from the following description are attained by the structure illustrated in the accompanying drawings in which—

Figure 1 is a front elevation of the head of a stitcher of the type described, only the operating parts essential to understanding the present invention being illustrated.

Figure 2 is a view taken from the left hand side of Figure 1 with some of the parts being broken away to more clearly illustrate the essential mechanisms. The parts are shown with the thread lock and presser foot lock in functioning position.

Figure 3 is a view in the same direction, with some parts sectioned, showing the presser foot released by its cam on the main shaft of the machine.

Figure 4 is a view in the same direction, showing mainly the presser foot lock released by the manual control independently of its cam on the main shaft.

Figure 5 is a view in the same direction, showing the thread lock released by its cam on the main shaft.

Figure 6 is a similar view showing the thread lock released by the manual control independently of its cam on the main shaft.

Aside from the presser foot and thread lock devices, the machine corresponds to the Goodyear type of stitchers familiar to those skilled in the art and includes a pedestal 1, a table or head 2 having spaced brackets 3 journaling the main cam shaft 4. The thread lock cam disk 5 includes the face cam groove 6 receiving the cam roller 7 on the end of cam lever 8. The presser foot lock cam disk 9 includes the face cam groove 10 which receives roller 11 on cam lever 12.

B indicates the work support bracket on which the shoe sole S rests. The operating ends of the usual curved awl and needle are shown at 13 and 14 respectively and oscillate about a common axis A in the usual manner.

A presser foot arm 16 (Figure 3) oscillates about an axis 15 and its inner end 17 is pivotally connected to a forked jaw 18 on a rod 19 slidably mounted in a sleeve 20 having a pivotal mounting member 21 on a pin 22 on the machine frame. The lower end of sleeve 20 terminates in a jaw 23. The lower end of rod 19 has a steep square thread, and a nut 24 on the threaded portion of the rod has a corrugated cylindrical ex-

terior and is rotatable in a dog 25, seated in jaw 23, when the dog is in the position shown in Figures 3 and 4. But if the dog be tilted so that the axis of its opening is disposed angularly to the axis of rod 19, as shown in Figure 2, nut 24 is held against rotation in the dog and rod 19 is held against axial movement.

A disk 26 is pivoted at 27 to cam lever 12 and a roller 28 is journaled on disk 26 at one side of pivot 27. Throughout the major portion of the cycle of operations cam groove 10 holds lever 12 in the position shown in Figure 2 and normally roller 28 tilts dog 25 to the position shown in Figure 2, holding nut 24 against rotation and therefore holding rod 19 against axial movement. Preferably roller 28 lifts upwardly on dog 25 moving sleeve 20 and rod 19 and the presser foot arm 16 far enough to tightly clamp the work against its support bracket B.

A plate 29 is threaded on the upper end of sleeve 20 and an adjusting screw 30, threaded through plate 29, bears against the mounting member 21 and is held in adjusted position by a set screw 31. A spring 32 yieldingly thrusts jaw 18, rod 19 and the inner end of presser foot arm 16 upwardly to maintain the presser foot in contact with the work.

During a short period in the cycle of operations of the machine the restricted high portion 10a of the cam depresses cam lever 12, disk 26 and roller 28, thereby unlocking the presser foot and releasing it from the positive grip on the work provided during the remainder of the cycle by the cam lever, dog 25 and rod 19 and permitting the work to be moved across bracket B by the usual feeding mechanism (not shown) subject only to the relatively slight friction by the presser foot exerted by spring 32.

Manually operated mechanism is provided for releasing the presser foot lock at any time in the cycle of operations of the machine. This mechanism comprises a rod 35 connected at its lower end to a foot treadle (not shown) and at its upper end to a lever 36 pivoted to a shaft 37 journaled in the machine head and connected by a link 38 to a vertically movable bar 39. The front face of bar 39 contacts a guide pin 40 on presser foot arm 16 and the rear face of member 39 has an offset track 41 engaging the opposing face of an arm 42 pivoted at 43. A lug 44 on arm 42 engages the right hand end of a lever 45 pivoted on pin 22 and the left hand end of the lever engages pin 47 on disk 26 aligned with the journal of roller 28.

When the treadle and rod 35 are depressed, slide 39 moves downwardly to the position shown in Figure 4 in which it thrusts arm 42 to the left, the thrust being transmitted through lever 45 to pin 47 which rotates disk 26 about its axis 27 and against the pull of spring 48 to move roller 28 to the position shown in Figure 4 in which dog 25 is freed from roller 28 to release nut 24 and permit it to be rotated by movement therethrough of rod 19 irrespective of the position of cam groove 10, lever 12 and disk pivot 27. Thereupon hook 49 on bar 39 engages pin 40 on the presser foot arm to tilt the same about its pivot 15 and lift the presser foot from the work, rod 19 moving downwardly and its threads rotating nut 24 freely in dog 25.

The thread lock cam lever 8 is pivoted at 50 (Figures 2, 5 and 6), and a link 51 connected thereto extends through a sleeve 52. Nuts 53 on link 51 form means for adjusting the effective length of link 51. Sleeve 52 has a lateral stem

5 52a (Figures 1 and 6) journaled in a collar 54 provided with an arm 54a. A crank shaft or bell crank lever 55 journaled on the machine head has an arm 55a pivoted to arm 54a. Another arm 55b has a notched outer end for receiving the corresponding end of a lever 56 pivoted on a shaft 57. The other end of lever 56 is shaped to oppose the surface of a grooved thread guide 58 to lock the thread T against being drawn through the machine by the thread take up 59 (Figures 1 and 2) or otherwise.

When the low portion 6a of cam 6 engages roller 7, lever 8 is moved to the position shown in Figure 5, drawing link 51, sleeve 52, collar 54 and arm 55a to the left and thrusting arm 55b in an anti-clockwise direction and lever 56 in a clockwise direction to release the thread. During the remainder of the cycle, cam 6, lever 8, link 51, collar 54 and crank arms 55a and 55b and lever 56 positively hold the thread locking elements in locking position.

When the treadle is depressed to release the presser foot, as in withdrawing the work, it is necessary to release the thread lock also. Downward movement of rod 35 and the clockwise rotation of shaft 37 rotates crank 60 on shaft 37 in a clockwise direction and moves a link 61 downwardly (Figure 6). The upper end of link 61 is connected to stem 52a (Figures 1 and 6) and may pull the latter downwardly from the position shown in Figures 2 and 5 to that shown in Figure 6.

As link 51 anchors sleeve 52 and the upper end of link 61 against movement to the right, the downward movement of link 61, bringing arm 54a from the inclined position of Figure 5 to the horizontal position of Figure 6, causes crank shaft 55 to turn in an anti-clockwise direction and causes lever 56 to turn in the opposite direction and release the thread.

Spring 65 returns the treadle rod and all the parts actuated thereby to normal position whenever pressure on the treadle is released.

The construction described provides a thread lock applied by levers and links rather than by spring pressure but, nevertheless, the pressure on the thread may be readily adjusted by shifting nuts 53.

The construction also provides a positive lock for the presser foot for any given thickness of work and does not depend upon the proper spacing of a series of ratchet teeth relative to the presser foot and work-supporting bracket as is required in the ratchet type locks previously used as illustrated, for example, in Patent 1,921,277, issued to the present applicant.

With the spring actuated thread locks and ratchet actuated presser foot locks as previously used, it has been customary to adjust the locking elements every couple weeks or so to maintain their effectiveness, whereas machines with the present locking structure have been run without adjustment for a period of six months.

It will be understood that either the thread lock or the presser foot lock described herein may be used independently of each other but the preferred arrangement contemplates the use of both of these locks in association with each other, and their manual release by a common mechanism.

The principles of the invention may be embodied in structures differing in details from those illustrated and described herein and the exclusive use of such modifications as come within the scope of the claims is contemplated.

What is claimed is:

1. In a stitching machine, a thread lock including a thread engaging member, cam mechanism for positively holding said member against the thread during a portion of the cycle of operations of the machine and for positively releasing the thread from said member during another portion of said cycle, and manually operable means for releasing the thread engaging member of the lock at any point in the cycle of operations of the machine.
2. In a stitching machine, a thread lock including a thread engaging element, a device actuated mechanically during each cycle of operation of the machine, a device arranged to be actuated manually at any point in said cycle, a linkage pivotally connected at its ends to said devices respectively, each of said devices upon being actuated swinging said linkage about its connection to the other device as an anchorage to positively move said element towards and from the thread.
3. In a stitching machine, a thread lock, a device actuated mechanically during the normal operation of the machine, a device arranged to be actuated manually at the will of the operator, members pivoted to each other and connecting said devices, each of said devices when actuated oscillating said members about a part of the other device as an anchorage, and an element having a connection to said members and movable positively thereby, when either of said devices is actuated, to control said thread lock.
4. In a stitching machine, a thread lock including a thread engaging element, a member oscillated during the cycle of operation of the machine, and a member arranged to be oscillated manually, each of said members having a fixed pivot, a linkage connected at its ends to said members respectively, a lever having one arm connected to said element and having its other arm connected to said linkage, each of said members, when oscillated, moving said linkage about its connection to the other member to actuate said lever to positively move said element to engage and disengage the thread.
5. In a stitching machine, a thread lock including a thread engaging element, a cam actuated lever, a bell crank with its arms pivotally connected to said element and said lever respectively whereby cammed movement of said lever swings said bell crank about its pivot to oscillate said element to release and engage the thread, a manually actuated part, and a connection between the same and said bell crank whereby movement of said part swings said bell crank about its pivot to positively oscillate said element to release and engage the thread.
6. In a stitching machine, a thread lock including a thread engaging member and a cam driven lever for actuating the same to positively clamp the thread during a portion of the cycle of operation of the machine, a presser foot including a thrust-transmitting arm and a cam driven lever for actuating the same to positively hold the presser foot against the work during a portion of the cycle of operation of the ma-
- chine, the respective cams each having portions automatically releasing said lock and presser foot at desired points during said cycle, and a part operatively connected to said member and presser foot for manually releasing said lock and presser foot simultaneously at any time during said cycle.
7. In a stitching machine, a thread lock including a thread engaging element, a cam driven lever, a pair of pivotally connected links connecting said lever and said element, a device for limiting the pivotal movement of said links whereby said lever may move said element to clamp the thread, a part operable to shift said device to release said thread lock, a presser foot including a thrust-transmitting arm and a cam driven lever, a connection between said lever and said arm for holding them against relative movement to hold said presser foot in work clamping position, a member operable to release said arm from said connection, and means actuated by a single manual operation for actuating said part and member simultaneously at any point in the cycle of operation of the machine.
8. In a stitching machine, a thread lock including a thread engaging element and a lever for actuating the same and having a fixed pivot, an operating shaft, a cam thereon, means movable positively in opposite directions by said cam and having a link connection to said lever, a manually operated means having a link connection to said lever, each of said means and its link connection forming an anchorage for the other link connection and each of said means being operable independently of the operation of the other of said means to move said lever and the element actuated thereby to and from the thread.
9. In a stitching machine, a thread lock including a thread engaging element, a cam operated member, a manually operated device, a lever having a pivotal connection at one end to said element, a linkage pivotally connected at its ends to said lever and to said member respectively, a linkage pivotally connected at its ends to said lever and said device respectively, said second-mentioned linkage swinging on its pivotal connections to said lever and device to accommodate movement of said lever by said member and said first-mentioned linkage, and said first-mentioned linkage swinging on its pivotal connections to said lever and member to accommodate movement of said lever by said device and said second-mentioned linkage.
10. In a stitching machine, a thread lock including a thread engaging member and cam operated mechanism positively thrusting said member against the thread during a portion of the cycle of operation of the machine, a presser foot, a cam operating mechanism positively thrusting said presser foot against the work during a portion of said cycle, said cam mechanisms automatically releasing said thread lock and said presser foot at desired points during said cycle, and a manually operable part for simultaneously releasing said lock and said presser foot by the operator at any time during said cycle.

EUGENE G. WOLF.
